Patented Aug. 21, 1956

178,566

VENDING MACHINE FOR ICE CREAM BARS OR THE LIKE

Fred Hebel, Wilmette, Ill., assignor to Fred Hebel Corporation, Addison, Ill., a corporation of Illinois

Application October 21, 1955, Serial No. 38,516

Term of patent 14 years

(Cl. D52—3)

Fig. 1

Fig. 2

Figure 1 is a front view, slightly in perspective, of the vending machine for ice cream bars or the like, showing my new design; and

Figure 2 is a side elevational view thereof.

The side of the vending machine not shown is substantially the same in appearance as the side disclosed in the drawing.

I claim:

The ornamental design for a vending machine for ice cream bars or the like, as shown and described.
